UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

PATTERN MECHANISM FOR LOOMS.

1,322,731.

Specification of Letters Patent. Patented Nov. 25, 1919.

Application filed April 3, 1919. Serial No. 287,303.

To all whom it may concern:

Be it known that I, ALONZO E. RHOADES, of Hopedale, in the county of Worcester and State of Massachusetts, have invented 5 certain new and useful Improvements in Pattern Mechanisms for Looms, of which the following is a specification.

The present invention consists in improvements upon the pattern mechanism set forth 10 in an application for Letters Patent of the United States filed by me September 16, 1918, Serial No. 254,326. That application relates 15 to a pattern mechanism particularly organized for terry looms. The pattern mechanism controls the beat-up motion, the let-off, and the let-back of a terry loom so that in weaving a Turkish towel, for example, plain and terry stripes of different widths and different distributions may be woven and the 20 plain weave is compact and properly joined to the terry weave.

The present improvements consist in mechanism for varying the extent of the weaving during each repetition of the pattern. That is to say, in weaving Turkish 25 towels, the present mechanism enables the length of the towels to be varied as desired without affecting the capacity of the pattern mechanism to vary the width and distribution of the plain and terry stripes.

The present improvements are illustrated in the accompanying drawings, wherein—

Figure 1, is a plan view of the improved pattern mechanism. Fig. 2, is a vertical cross section. Fig. 3, is a vertical longitudinal section. Fig. 4, is a side view of one of the pawl lifters. Fig. 5, is a perspective view of one of the pawl lifters. Fig. 6, is a sectional detail illustrating the connections between one of the pawl lifters and its supporting mechanism.

In the drawings reference numerals, corresponding to those employed in said prior application, are used to indicate the same 45 parts as disclosed in that application. Reference letters are employed to indicate the new parts which are not in said prior application.

As in said prior application the pattern 50 mechanism controls the beat-up motion, the let-back and the let-off of a terry loom through two transmitters 10 and 11, each

shown as a lever pivoted at its outer end. Wire 12, leads from the inner end of the forward transmitter 10, to the let-back motion, which in itself constitutes no part of the present invention. It suffices to know 55 that whenever the let-back transmitter 10, is lifted its motion is transmitted through the wire 12, and the cloth and warp are let 60 back. As soon as the transmitter 10, drops, the let-back action ceases.

A wire 13, leads from the inner end of the rear or terry transmitter 11, to the beat-up motion which in itself constitutes no part 65 of the present invention. It suffices to know that when the terry transmitter is down the terry weave continues; and, that when said transmitter is raised, plain weaving is done. A second wire 14, leads from the inner end 70 of the terry transmitter to the terry let-off which through the movement of the transmitter 11, is rendered operative during the terry weave and inoperative during the plain weave as set forth in detail in said 75 prior application.

The movements of the transmitters 10 and 11, are affected in the desired sequence by the pattern mechanism. This mechanism comprises a rotating pattern wheel 55, 80 which carries a series of adjustable cams indicated at 56, 58 and 59, which coöperate with a downwardly projecting foot 66, of the terry transmitter 11. The cam wheel also supports an adjustable cam carrier 60, 85 having a series of cams 61, coöperating with the downwardly projecting foot 67, of the let-back transmitter 10. The pattern wheel 55, has a hub 53, which turns on a fixed stud 54. Fastened to the hub of the cam 90 wheel is a ratchet wheel 52. This ratchet wheel coöperates with a pawl lever 46, pivoted at 47. An actuator consisting of a pawl 51, is pivoted at 50, to the upper end 95 49, of the pawl lever 46. The pawl lever 46, is rocked back and forth in timed relation to the weaving by mechanism driven from the power shaft of the loom as set forth in the aforesaid application. It suffices to know that the lever 46, is recipro- 100 cated so that the pawl 51, at each reciprocation engages one of the teeth of the ratchet wheel 52, thereby feeding the pattern wheel 55 around step by step. Backward slip of

the ratchet wheel is prevented by a pivoted detent 74.

A towel is woven at each rotation of the pattern wheel. By changing the pattern cams 56, 58, 59 and 60, on the pattern wheel, and by adjusting their circumferential positions on that wheel, the location and width of the plain and terry stripes can be varied to suit the needs of the manufacturer.

10 In all of the respects thus far mentioned the pattern mechanism here illustrated is like that set forth in the aforesaid prior application.

15 The purpose of the present invention is to enable different lengths of towels to be woven without interfering with the capacity of the pattern mechanism in varying the width and distribution of the plain and terry stripes. This object is achieved by 20 the employment of controllers for the pattern cam actuator consisting of pawl lifters A, of varying lengths which are applied to the pattern mechanism so as to render idle the pattern actuating pawl 51, or pattern cam actuator, thereby stopping the progressive advance of the pattern wheel for varying intervals and hence varying the length of the towels woven. One of the controllers or pawl lifters is shown in detail in Fig. 4.

25 30 As shown in this figure and in Fig. 2, it is a curved plate, which extends horizontally over a portion of the teeth of the ratchet 52. The leading end of this pawl lifter is beveled as shown at B, in Figs. 3 and 4. Accordingly, as the ratchet wheel 52, and the pawl lifter advance in the direction of the arrow shown in Fig. 3, the pattern actuating pawl 51, encounters the beveled leading edge B, of the pawl lifter A, so that the 35 40 pawl is lifted away from the teeth of the ratchet 52, and is maintained lifted as shown in Fig. 3. Consequently the pattern actuating pawl 51, as it is reciprocated by the pawl lever 46, simply rides idly back and forth upon the pawl lifter A, without 45 50 imparting any movement to the ratchet wheel. Hence, the ratchet wheel and the pattern wheel 55, remain stationary and are idle so long as the actuating pawl is rendered idle by the pawl lifter A.

55 In order that the pattern actuating pawl 51, may again coöperate with the ratchet wheel 52, so as to resume the forward feed of the cam wheel, mechanism is provided for feeding the pawl lifter independently of the pattern cam wheel 55. The pawl lifter A, has a flange C, through which it is secured to a ratchet plate D, as indicated in Figs. 3 and 6. This plate D, is adjustably secured by bolts E, and slots F, to the pawl lifter carrier G. By means of this bolt and slot connection the plate D, may be circumferentially adjusted upon the carrier G. The carrier G, has a hub H, which turns 60 65 freely upon the hub 53, of the pattern

wheel. The ratchet wheel 52, carries a stud I. This stud is circumferentially adjustable upon the ratchet wheel by means of the bolts J and slots K. Normally, that is to say during the greater portion of the rotation of the ratchet wheel 52, the rear face L, of the carrier G, is held against the leading end of the block I, by means of a spring M, connected at opposite ends to the carrier G, and the cam wheel 55, as shown in Fig. 2. 75 Accordingly, during the normal advance of the ratchet wheel 52, the pawl lifter carrier G, is moved forwardly with the ratchet wheel and pattern-cams by the stud I. This action continues until the pattern pawl 51, 80 is encountered and lifted by the pawl lifter A.

Thereupon, the pawl lifter is fed forwardly step by step independently of the ratchet 52, and without imparting any 85 movement to said ratchet wheel or to the pattern wheel 55. For this purpose, the plate D, which carries the pawl lifter (and might be in one piece therewith) is provided with a set of ratchet teeth N. These 90 ratchet teeth coöperate with an auxiliary actuator consisting of a lifter pawl O, which is pivoted at P, to the pattern pawl 51, and partakes of its reciprocation. Concurrently with the advance of the pawl 95 lifter to the position where it renders the pawl 51 idle, the leading tooth N, of the pawl lifter ratchet is brought within reach of the lifter pawl O. Accordingly, as soon as the pawl 51, becomes idle, the pawl O, 100 becomes active. Thereupon the lifter pawl O, in its reciprocation feeds the pawl lifter and the parts connected therewith forwardly step by step thus feeding the pawl lifter beneath the pawl 51, and carrying 105 the rear face L, of the pawl lifter carrier G, step by step away from the stud I, and putting the additional tension upon the spring M. Backward movement of the pawl lifter carrier G, under the stress of 110 its spring M, is prevented by a secondary detent Q, which is pivoted at R, to the primary detent 74. During this feeding action of the lifter pawl O, the ratchet wheel 52, and the cam wheel 55, remain 115 stationary, until the pawl lifter A, is fed forwardly beyond the pattern pawl 51. Thereupon the pawl 51, again engages the ratchet 52. Thereafter the normal feed of the ratchet wheel 52, and the pattern wheel 120 55, is resumed.

As shown in Fig. 3, the pawl lifter A, is of smaller circumferential length than the set of ratchet teeth on the plate D, so that during a period following the resumption 125 of the action of the pattern pawl 51, the lifter pawl O, continues to feed the pawl lifter concurrently with the feed of the ratchet 52, by the pawl 51. This feeding action of the lifter pawl O, continues until 130

the last tooth, of the ratchet plate D, is fed forwardly beyond reach of the detent Q. As soon as this occurs any forward movement of the ratchet plate D, by the lifter pawl O, is neutralized by a corresponding backward movement of the carrier G, through its spring H, as the pawl O, in its reciprocation moves backwardly. This idle forward and backward movement of the 10 carrier G, and the pawl lifter continues until the stud I, on the ratchet wheel 52, catches up with the carrier G, and encounters the rear face L, of said carrier. Thereafter the carrier G, and its associated 15 parts is fed forwardly concurrently with the ratchet wheel 52, through the stud I.

The subsequent forward advance of the pattern mechanism soon carries the carrier G, and its associated parts entirely out of 20 reach of the lifter pawl O, and detent Q. In order to maintain these parts in position ready again to act proper provision is made. The pawl O, has a laterally projecting finger S, which overlies the pawl 51, as shown 25 in Figs. 1, 2 and 3. Accordingly, when the ratchet plate F, has passed beyond the pawl O, said pawl is maintained uplifted by the finger S resting on top of the pawl 51. Likewise, the secondary detent Q, has a 30 similar laterally projecting finger T, Figs. 1 and 3, which overlies the primary detent 74, and limits the downward swing of the detent Q.

The overall length of towels or the extent 35 of each repeat of the weave is dependent upon the circumferential length of the pawl lifter A. By removing the pawl lifter altogether a short length of towel is woven. Towels of greater lengths can be woven by 40 the insertion of pawl lifters A, of increasing lengths. Figs. 4 and 5 illustrate pawl lifters of different lengths.

In order to change the pawl lifters A, the 45 bolts E, are removed. Thereupon the ratchet plate D, with the attached pawl lifter is taken out. The pawl lifter is then detached from the ratchet plate D, and a different pawl lifter is attached thereto. The ratchet plate with the new pawl lifter is 50 again fastened to the carrier G, by the bolts E. The pawl lifter A, might be in one piece with the ratchet plate D, but less economically so, since that would involve as many sets of ratchet teeth as there are pawl lifters of varying lengths. The pawl lifter A, with its attaching flange C, is a simple economical construction so that a large variety of pawl lifters can be furnished at 55 small cost.

60 The circumferential adjustment of the ratchet plate D, upon the carrier G, enables the ratchet teeth N, to be accurately adjusted with respect to the teeth on the ratchet wheel 52. The circumferential adjustment of the stud I, enables it to be po-

sitioned so as to catch up with the carrier G, just as the pawl O, ceases to act upon the ratchet teeth N.

As indicated in Fig. 2, the pawl lifter or controller is located by the stud I at a position remote from the pattern cams 56, 58, 59 and 60. Accordingly, the pawl lifter never acts concurrently with the pattern cams so that it does not interfere with the width and distribution of the stripes of 75 plain and terry weave. The pawl lifter acts during the weave of the towel body and the length of that portion of the weave is determined by the positions of the first and last pattern cams 56 and 59, on the 80 pattern wheel 55. In other words, the pawl lifter or controller A, is advanced by the pattern cam actuator 51, concurrently with the pattern cams during the period when said cams are active, at which time the 85 controller is idle. The controller is thus normally idle. When, however, the controller functions it renders the actuator 51, idle, and the feed of the pattern cams ceases. This occurs when the pattern cams are at 90 an idle or inactive position. Concurrently with the cessation of action of the actuator 51, the auxiliary actuator O comes into action and advances the controller A without imparting movement to the pattern cams. 95

The lifter carrier G, has a counterbalancing enlargement U, diametrically opposite to the pawl lifter.

I claim—

1. A pattern mechanism for looms having a pattern wheel, a ratchet wheel connected therewith, a pattern pawl coöperating with said ratchet wheel to move said pattern wheel, and a primary detent engaging said ratchet wheel to prevent backward movement thereof, in combination with a stud moving with said ratchet wheel, a pawl lifter for said pattern pawl, a pawl lifter carrier, a set of ratchet teeth on said carrier, a spring normally holding said pawl carrier against said stud, a lifter pawl pivoted to said pattern pawl which coöperates with said set of ratchet teeth when said stud brings said set of ratchet teeth into the range of action of said lifter pawl, a secondary detent pivoted to the primary detent and engaging said set of ratchet teeth to prevent backward movement of the pawl lifter during the feeding action of the lifter pawl, a stop finger on the lifter pawl overlying the pattern pawl, and a stop finger on the secondary detent overlying the primary detent. 115

2. A pattern mechanism for looms having a pattern wheel, a ratchet wheel connected therewith, a pattern pawl coöperating with said ratchet wheel to move said pattern wheel, and a primary detent engaging said ratchet wheel to prevent backward movement thereof, in combination 120

- with a stud moving with said ratchet wheel, a pawl lifter for said pattern pawl, a pawl lifter carrier, a set of ratchet teeth on said carrier, a spring normally holding said pawl carrier against said stud, a lifter pawl pivoted to said pattern pawl which coöperates with said set of ratchet teeth when said stud brings said set of ratchet teeth into the range of said lifter pawl, and a secondary detent pivoted to the primary detent and engaging said set of ratchet teeth to prevent backward movement of the pawl lifter during the feeding action of the lifter pawl.
- 15 3. A pattern mechanism for looms having a pattern wheel, a ratchet wheel connected therewith, a pattern pawl coöperating with said ratchet wheel to move said pattern wheel, and a primary detent engaging said ratchet wheel to prevent backward movement thereof, in combination with a stud moving with said ratchet wheel, a pawl lifter for said pattern wheel, a pawl lifter carrier, a set of ratchet teeth on said carrier, a spring normally holding said pawl carrier against said stud, a lifter pawl which coöperates with said set of ratchet teeth when said stud brings said set of ratchet teeth into the range of action of said lifter pawl, and a secondary detent engaging said set of ratchet teeth to prevent backward movement of the pawl lifter during the feeding action of the lifter pawl.
4. A pattern mechanism for looms having a pattern wheel, a ratchet wheel connected therewith, and a pattern pawl coöperating with said ratchet wheel to move said pattern wheel, in combination with a stud moving with said ratchet wheel, a pawl lifter for said pattern pawl, a pawl lifter carrier, a set of ratchet teeth on said carrier, a spring normally holding said pawl carrier against said stud, a lifter pawl which coöperates with said set of ratchet teeth when said stud brings said set of ratchet teeth into the range of action of said lifter pawl, and a secondary detent engaging said set of ratchet teeth to prevent backward movement of the pawl lifter during the feeding action of the lifter pawl.
5. A pattern mechanism for looms having a pattern wheel, a ratchet wheel connected therewith, and a pattern pawl coöperating with said ratchet wheel to move said pattern wheel, in combination with a stud moving with said ratchet wheel, a pawl lifter for said pattern pawl, a pawl lifter carrier, a set of ratchet teeth on said carrier, a spring normally holding said pawl carrier against said stud, and a lifter pawl which coöperates with said set of ratchet teeth when said stud brings said set of ratchet teeth into the range of action of said lifter pawl.
6. A pattern mechanism for looms having a pattern wheel, a ratchet wheel connected therewith, an actuating pattern pawl coöperating with said ratchet wheel to move said pattern wheel, in combination with a stud moving with said ratchet wheel, a pawl lifter for said pattern pawl, a pawl lifter carrier, a set of ratchet teeth on said carrier, which coöperates with said set of ratchet teeth when said stud brings said set of ratchet teeth into the range of action of said lifter pawl.
7. A pattern mechanism for looms having a pattern wheel, a ratchet wheel connected therewith, a pattern pawl coöperating with said ratchet wheel to move said pattern wheel, and a primary detent engaging said ratchet wheel to prevent backward movement thereof, in combination with a pawl lifter for said pattern pawl, a pawl lifter carrier normally moving with said ratchet wheel, a set of ratchet teeth on said carrier, a lifter pawl pivoted to said pattern pawl which coöperates with said set of ratchet teeth when brought into the range of action of said lifter pawl, a secondary detent pivoted to the primary detent and engaging said set of ratchet teeth to prevent backward movement of the pawl lifter during the feeding action of the lifter pawl, a stop finger on the lifter pawl overlying the pattern pawl, and a stop finger on the secondary detent overlying the primary detent.
8. A pattern mechanism for looms having a pattern wheel, a ratchet wheel connected therewith, a pattern pawl coöperating with said ratchet wheel to move said pattern wheel, and a primary detent engaging said ratchet wheel to prevent backward movement thereof, in combination with a pawl lifter for said pattern pawl, a pawl lifter carrier normally moving with said ratchet wheel, a set of ratchet teeth on said carrier, a lifter pawl which coöperates with said set of ratchet teeth when said stud brings said set of ratchet teeth into the range of action of said lifter pawl, a secondary detent engaging said set of ratchet teeth to prevent backward movement of the pawl lifter during the feeding action of the lifter pawl, a stop finger on the lifter pawl overlying the pattern pawl, and a stop finger on the secondary detent overlying the primary detent.
9. A pattern mechanism for looms having a pattern wheel, a ratchet wheel connected therewith, and a pattern pawl coöperating with said ratchet wheel to move said pattern wheel, in combination with a pawl lifter for said pattern pawl, a pawl lifter carrier normally moving with said ratchet wheel, a set of ratchet teeth on said carrier, and a lifter pawl which coöperates with said set of ratchet teeth when brought into the range of action of said lifter pawl.

10. A pattern mechanism for looms having pattern cams, and an actuator therefor, in combination with a normally idle controller which is advanced by said actuator concurrently with the advance of said cams, 5 said controller rendering said actuator idle when said cams are moved to inactive position, and an auxiliary actuator for advancing said controller without imparting movement to the pattern cams, the pattern cam 10 actuator being idle when the auxiliary actuator is active.

In witness whereof, I have hereunto signed my name.

ALONZO E. RHOADES.
